SAFETY RAZOR BLADE HOLDER

Awald R. Fritz, Michigan City, Ind.

Application February 4, 1935, Serial No. 4,929

1 Claim. (Cl. 30—101)

The invention relates to a blade holder and more especially to a safety razor blade holder.

The primary object of the invention is the provision of a holder of this character, wherein a double cutting edge safety razor blade can be conveniently held for the purposes of the honing or stropping of both cutting edges of said blade, the blade being readily placed within and removed from the holder without liability of injury resultant from contact of the fingers of the hand with the cutting edges as opposite ends of the blade will be exposed for the engagement of the fingers therewith free of the holder.

Another object of the invention is the provision of a holder of this character, wherein the hinge for the clamping plates is of a construction to permit the convenient and easy introduction into a handle part which functions to hold the clamping plates in position for the clamping of the safety razor blade which may be properly angled for honing and stropping purposes.

A further object of the invention is the provision of a holder of this character, wherein the safety razor blade will be firmly and securely held so that both cutting edges thereof may be singly exposed for the honing and stropping of the same without liability of the slipping of the blade during this operation, the cutting edge being cleared of the clamping plates to avoid damage to such edge when honing or stropping the same.

A still further object of the invention is the provision of a holder of this character, wherein a safety razor blade of the double cutting edge type when held within the clamping plates will be firmly gripped between such cutting edges so that these edges will not be damaged from contact with the clamping plates and especially during honing or stropping.

A still further object of the invention is the provision of a holder of this character, which is simple in construction, thoroughly reliable and efficient in its purpose, conveniently handled, enabling a safety razor blade to be readily mounted within and removed from the said holder, strong, durable, and inexpensive to manufacture.

With these and other objects in view the invention consists in the features of construction, combination and arrangement of parts as will be hereinafter more fully described in detail, illustrated in the accompanying drawing disclosing the preferred embodiment of the invention and pointed out in the claim hereunto appended.

In the accompanying drawing:

Figure 1 is a side elevation of a handle con-

structed in accordance with the invention showing a safety razor blade held thereby.

Figure 2 is an enlarged sectional view on the line 2—2 of Figure 1 looking in the direction of the arrows.

Figure 3 is an enlarged perspective view of the clamping plates of the holder.

Figure 4 is a vertical transverse sectional view through the plates showing the same in open position.

Figure 5 is a plan view of one of the plates.

Figure 6 is a plan view of the other plate.

Similar reference characters indicate corresponding parts throughout the several views in the drawing.

Referring to the drawing in detail, the holder comprises a pair of clamping plates 10 and 11, respectively, these being flat and of substantially rectangular shape, the plate 11 being of a greater length than the plate 10. The plate 10 is provided with a pair of spaced holes 12 while the plate 11 is provided with a companion pair of spaced embossed studs or lugs 13, these being of less size than the holes 12 but are adapted to be received within the latter. The lugs serve to engage matched holes within a safety razor blade 14 of the double cutting edge type, it being understood, of course, that the plate 11 is of a length less than the length of the blade 14 so that the ends of the latter will be exposed for gripping engagement by the hand when the blade is clamped between the plates.

The plate 10 at its rearmost edge is formed with a substantially U-shaped outwardly angled web portion 15 having the outwardly arched bridge 16 bent at an angle thereto and terminating in pivot ears 17, these being received in pivot eyes 18 cut and formed from the offset web portion 19 of the plate 11 and in this manner these plates 10 and 11 are hinged together for the clamping of the razor blade 14 therebetween. The web portion 19 of the plate 11 is formed with a stop tongue 20 for engaging the bridge 16 to limit the swinging of the plates 10 and 11 when moved to open relation with respect to each other and in this position the blade 14 is readily removable from between the said plates. The pivot eyes 18 are tubular in shape and permit easy introduction into a tubular head 21 of a handle 22, the head 21 being longitudinally slotted and formed with opposed resilient gripping cheeks 23, these being spaced to accommodate therebetween the webs 15 and 19 of the plates 10 and 11 when brought together in clamping relation to each other and in this manner the head when embracing the 55

eyes 18 and the web portions 15 and 19 of the plates 10 and 11 will hold the same in position for clamping the blade 14 as is clearly shown in Figure 1 of the drawing.

5 The cheeks 23 of the head 21 are of a width to overlie the web portions 15 and 19 of the plates 10 and 11, with the latter protruded therefrom. The plates 10 and 11 at their outer longer edges are beveled at 24 to permit of the proper angular 10 lay of the blade 14 when clamped by the cheeks and held within the head 21 of the handle 22 when positioned for honing or stropping.

15 It will be obvious from Figures 1, 2 and 4 of the drawing that when the blade 14 is clamped between the plates 10 and 11 the double cutting edges thereof will be clear of contact with metal or the plates 10 and 11 and the webs 15 and 19 of the same so that no damage can result to the 20 said cutting edges of the blade when clamped by the plates 10 and 11 and during the stropping or honing period.

25 The handle 22 is of considerable length for convenience in the manipulation of the holder during stropping or honing of the blade 14, it being obvious from Figures 3 and 4 of the drawing that when the hinge plates are released from the head 21, these plates can be swung to open position and the blade 14 freely removed by gripping the exposed ends of the plates by the fingers of a hand of the user of the holder without 30 injury from cuts by the cutting edges of said blade.

The web portion 15 has the relatively large slot or opening 25 as formed thereby so that when the blade 14 becomes arched by pressure from the thumb and index finger against opposite ends thereof on removing such blade the innermost cutting edge of the blade will not come in contact with the plate 10 when the blade is held between the plates 10 and 11.

5 The outward angle of the portions 15 and 19 which is also present with the plates 10 and 11 10 enables the gripping of the blade at the outer portion thereof and next to the lugs 13, this being apparent from Figure 2 of the drawing.

What is claimed is:

A holder of the character described comprising 15 a pair of plates forming clamping cheeks, pivot eyes formed on one of said plates, a web portion on the other plate and angled outwardly therefrom, an outwardly arched bridge bent at an angle from said web portion and having terminal 20 pivot ears engaged in said eyes for swingingly connecting the plates with each other, a leaf spring extension formed on the plate having the eyes and engageable with the arched bridge for sustaining the plates together or separated from 25 each other, studs struck from one of said plates and seated in the other plate when both plates are together for the holding of a safety razor blade between the latter and means for fitting with the eyes and constituting a handle. 30

AWALD R. FRITZ.
